BINDER

Henry T. Adams, Chicago, Ill.

Application August 2, 1937, Serial No. 157,053

5 Claims. (Cl. 129—8)

This invention relates to a binder for perforated paper sheets, checks, etc.

Heretofore it has been common to use hinged or jointed rings in loose-leaf books and binders, and in such constructions it has usually been necessary to employ either a very few rings which permitted leaves to be torn out very easily; or when more rings were used, a complicated structure was necessary. It has also been known that fixed binders could be employed with a large number of rings formed of a plastic material, by which the perforated paper could be confined securely, but could not be removed because of the fixed character of the rings.

An object of the present invention is to provide a structure in which a large number of rings can be employed without the use of joints or hinges, while at the same time permitting sheets to be removed or inserted. A further object is to provide a binder structure employing a large number of confining rings or prongs and in which the operating or moving mechanism is extremely simple. A further object is to provide a binder of skeleton or extremely simple construction, which is effective as a confining means and which may be later inserted within a more permanent binder for storage or filing purposes. Other specific objects and advantages will appear as the specification proceeds.

The invention is illustrated, in a preferred embodiment, by the accompanying drawings, in which—

Fig. 1 is a plan view of a binder embodying my invention, the binder being shown in closed position; Fig. 2, a similar plan view of the binder in open position; Fig. 3, a transverse sectional view, the section being taken as indicated at line 3 of Fig. 1; Fig. 4, a transverse sectional view, the section being taken as indicated at line 4 of Fig. 2; Fig. 5, a broken sectional view, the section being taken as indicated at line 5 of Fig. 1; Fig. 6, a broken sectional view, the section being taken as indicated at line 6 of Fig. 1; Fig. 7, a broken plan view of the permanent metal binder or clip; Fig. 8, a broken plan sectional view of the outer frame member only, the section being taken as indicated at line 8 of Fig. 3; Fig. 9, a broken plan sectional view of the inner rotatable member; and Fig. 10, a transverse sectional view, the section being taken as indicated at line 10 of Fig. 4.

In the illustration given, A designates a fixed frame equipped at spaced intervals with fixed ring prongs A'; B designates an inner rotatable frame equipped at spaced intervals with rings or prongs secured in slidable relation to the prongs

A'; and C, a spring clip or permanent binder to which the frame member A may be conveniently attached for filing purposes, etc.

The frame member A may be of any suitable construction and of any desired material. In the illustration given, it consists of a longitudinal bottom frame 10, to which, at spaced intervals, are fixed the prongs A'. The prongs A' are pressed inwardly along their length to form a reinforcing groove 11, this groove serving as a means for also locking the movable prongs B' in slidable relation to prongs A'. It will be observed that the fixed prongs A' are separated near their top portion so as to provide an intervening gap or opening to permit the insertion or removal of perforated sheets.

The bottom frame member 10 is preferably provided at its ends, and between the spaced prongs A', with outwardly curved ear portions 12. The outwardly flared portions 12 serve not only as reinforcing means for the bottom frame 10, but also provide, when arranged in a uniformly curved condition, as means for anchoring the metal directly to the back of a loose-leaf book or the like. The curved surfaces fit flat against the back and can be secured by rivets or other means, so as to form a sturdy and compact loose-leaf book. Because the loose-leaf book is of well known construction, it is not illustrated herein. If the loose-leaf book should have a flat back binding, the frame member 10, with the portions 12, can be made flat, so as to lie squarely against the flat backing. It will be understood that the frame 10 can be readily adapted to a loose-leaf back of any shape.

The inner member B may also be of any suitable construction or material. In the illustration given, it comprises a longitudinal frame or bridge member 13, equipped at spaced intervals with the prongs B' and with inwardly flared ears or curved members 14 between the prongs. The inwardly curved portions 14 serve to brace the metal frame and to form a strong support for the frame and prongs. As already stated, the prongs B' are provided with grooves which receive the inwardly extending ribs of prongs A', the ribs being formed by the grooves 11. Thus, the fixed prongs A' and the movable prongs B' are not only braced throughout their length by ribs or grooves, but also are confined in aligned slidable relation with each other, so that the movable prongs are constantly guided by the fixed prongs, and the two types of prongs mutually reinforce each other.

At each end, the frame member 13 is provided

with raised stepped end pieces 15 which are adapted to be engaged readily by the fingers or thumb, to facilitate the rotation of the inner member B.

5 The backing or clip member C may be of any suitable construction. In the illustration given, the clip member C comprises a spring body 16 equipped with inwardly turned ends 17. As a means for facilitating the insertion of the frame member 10 within clip or binder C, I prefer to turn some of the portions 12 downwardly, while leaving other portions extending upwardly. As shown more clearly in Figs. 5 and 6, it will be observed that the diverging portions 12 serve to 10 lock the member A securely about the flanges. The downwardly turned portions 12 may, if desired, be alternated with the upwardly curved portions 12; or, if desired, the downwardly turned portions may be formed at any desired position 15 along the frame 10.

In the operation of the device, the ends 15 are grasped to swing the inner prongs B' to the open position shown in Figs. 2 and 4. In this position, the perforated sheets may be inserted on 20 either of the fixed prongs A', or removed therefrom. After the sheets are in position, the end pieces 15 may be depressed in a circular movement to swing the prongs B' to the closed position shown in Figs. 1 and 3. The devices A and B 25 may be operated alone as a binder and need not be used in conjunction with a loose-leaf book or a clip such as is shown in C. For example, the members A and B may be used in the binding of catalogues, memoranda pads, checks, etc. When, 30 for example, the members are used for confining checks, it may be later desired to file away the checks in permanent clips, and the member A, containing the checks, etc., may be readily inserted within clip C by engagement between the 35 alternating ear portions 12 with the flanges 17.

When employed with a book having a backing, the ear portions 12 and frame 10 may be readily shaped to conform to the shape of the backing, and secured directly thereto by rivets or other suitable means.

40 The binder is of extremely simple construction, comprising only two main parts, which may be adapted readily for use with the other parts illustrated. The rotary movement produces a definite locking mechanism which may be operated readily, yet tends to remain in locked position under stress, and does not require the use of springs, as in the case of jointed rings. By this means, a large number of closely spaced 45 rings can be formed cheaply and manipulated easily, by means of which perforated sheets can be held in secure position within the binder.

While in the foregoing description I have shown a single example of one means for embodying the invention, it will be understood that the principle herein illustrated can be readily employed in a large variety of constructions, dif-

fering in form, but employing obvious forms of the invention and following the spirit of the invention. The means for closing the openings in the fixed rings can take on a variety of forms, either inside or outside of the fixed rings, and 5 can be adapted to form a curvilinear path about the fixed rings.

The foregoing detailed description has been given for clearness of understanding only and no unnecessary limitations should be understood 10 therefrom, but the appended claims should be construed as broadly as permissible in view of the prior art.

I claim:

1. In combination, a clip member provided 15 with inwardly turned flanges, a ring binder comprising a frame provided at spaced intervals with fixed rings each having a gap therein, a rotatable frame member within said frame and equipped with prongs adapted to close the gaps in said 20 rings, said frame being provided with bracing ears extending between said rings, said ears being turned downwardly to engage the flanges of said clip.

2. A ring binder for perforated sheets consist- 25 ing of two elements, one of the said elements comprising an integral frame equipped with fixed rings each having a gap therein, and the other of said elements comprising a rotatable bridge member extending the length of said frame and 30 equipped with prongs supported in alignment with said rings.

3. A ring binder for perforated sheets comprising an integral frame having a plurality of fixed rings supported at spaced intervals, said 35 rings having gaps therein, and an inner member consisting of spaced prongs and a bridge member connecting the same, said prongs being aligned with said ring members and serving to close said gaps when said bridge member is rotated within 40 said frame.

4. A ring binder for perforated sheets consisting of two elements formed from metal blanks, one of said elements comprising an outer frame having a plurality of fixed circular rings supported at spaced intervals, the rings each having a gap therein, and the other of said elements comprising an inner bridge member equipped with spaced prongs, the entire inner member being rotatable within said outer member, and said prongs being aligned with said rings to close the 45 gaps therein when said inner member is rotated.

5. A ring binder for perforated sheets comprising a frame equipped with fixed rings having a gap therein, and a rotatable frame member supported within said rings and having a straight wall along one side and prongs extending from the other side, said prongs being supported in alignment with said rings, and inwardly turned bracing ears formed between said prongs. 55

HENRY T. ADAMS.
